(57) **CLAIM**

The ornamental design for a high definition multimedia interface connector with an overmold on cable, as shown and described.

DESCRIPTION

FIG. 1 is a front perspective view showing our design for a high definition multimedia interface connector with an overmold on cable;

FIG. 2 is a top view thereof;

FIG. 3 is a bottom view thereof;

FIG. 4 is a right side view thereof, the claimed portion of which is a minor image to a left side view;

FIG. 5 is a front view thereof on a larger scale; and,

FIG. 6 is a rear view thereof.

The broken line portion of the figure drawings is included to show unclaimed subject matter only and forms no part of the claimed design.
